UNITED STATES PATENT OFFICE.

PIERRE THEODORE ALBERT LASSCHUIT, OF SCHOTEN, NEAR HAARLEM, NETHERLANDS, ASSIGNOR OF ONE-FOURTH TO PETER FREDRIK THOMSEN, OF THE HAGUE, NETHERLANDS, ONE-FOURTH TO JOHANN ANTON LUIJ, OF HAARLEM, NETHERLANDS, AND ONE-FOURTH TO WILHELMUS JOHANNES VAN DAM, OF THE HAGUE, NETHERLANDS.

GAS-BURNER.

1,146,943.

Specification of Letters Patent. Patented July 20, 1915.

Application filed October 25, 1913. Serial No. 797,210.

To all whom it may concern:

Be it known that I, PIERRE THEODORE ALBERT LASSCHUIT, a subject of the Queen of the Netherlands, residing at General 5 Cronjéstraat 15, Schoten, near Haarlem, Netherlands, have invented a certain new and useful Improvement in Gas-Burners, of which the following is a specification.

The present invention contemplates an 10 improved burner which is provided with a regulator for air and so constructed as to obviate the defects usually associated with gas burners suitable for use with gas at ordinary pressures of supply and of a greater 15 diameter than 10 centimeters. By this arrangement a complete mixture of the gas and air is produced, as also a thorough and even distribution of the mixture over the entire surface of the burner, while it is possible 20 to give the surface of the burner a much greater diameter than has been the case heretofore and at the same time to consume the gas at the ordinary pressure. Moreover with this burner individual 25 adjustments of the gas and air supply are not possible; by means of a common adjustment the same proportion can always be had.

The invention will now be described with reference to the accompanying drawings 30 illustrating an embodiment of the invention and in which:

Figure 1 is a side view, partly in section of a gas burner constructed according to the present invention; Fig. 2 is a longitudinal 35 section of the gas and air regulator, along the line A B of Fig. 1; Fig. 3 is a plan of the partially covered chamber or compartment for the mixture of air and gas. Fig. 4 is a detail of the revolving plate, which 40 covers the chamber. Fig. 5 is a plan of the entirely assembled arrangement.

In the drawing, *a* designates the gas inlet to the chamber *c*; a cock *b* in the inlet controls the supply.

45 The chamber *c* is partially covered by the solid sectors 2 and 4 (see Fig. 3), and the air may be admitted through the open sectors 1 and 3.

50 A revolving plate *e* (Fig. 4) is divided into sectors 1', 2', 3' and 4', corresponding to the sectors 1, 2, 3 and 4 of the air-chamber and is adapted to cover the latter; this plate can be rotatably adjusted around the

screw *k*. Of this plate *e* the sectors 2' and 4' are open and 1' and 3' are closed. It is 55 evident, that by turning the plate *e* the open sectors 1 and 3 of the chamber *c* can be partially or completely shut.

The plate *e* is formed with a projection *j*, which is connected with the arm *g* controlling the gas cock by a link *h* (see Fig. 5). A button *i* is fixed to the link *h*, by which it can easily be shifted. An adjustment of the link in either direction will by means of the arrangement employed produce a corresponding and simultaneous adjustment of the cock *b* and plate *e*. The arrangement moreover is such that the sectors 1' and 3' completely cover the air openings 1 and 3 of the chamber *c*, when the cock is completely 70 closed and leave them entirely open, when the cock is entirely open. By this arrangement a maximum supply of air is furnished simultaneously with a maximum supply of gas, and the supply of air is completely shut 75 off when the supply of gas ceases, while in the intermediate positions the degree of opening or closure of the cock and the corresponding openings or sectors for the supply of air, are in definite relation, so that with 80 any adjustment the supply of air is always properly proportioned to the supply of gas. An advantage arising from this construction is that the supply of air enters the chamber 85 from the top.

The gas that has entered through the inlet *a* into the chamber, by its tendency to rise, immediately comes into contact with the air that streams through openings in the upper part of said chamber, so that a complete 90 mixture takes place which produces a hot flame of equal size throughout.

The complete mixture of gas and air leaves the chamber by the conducting tube *d* and passes to the burner head, which may be 95 constituted by a circular box *m* with a cover *n* (which may be detachable), formed with perforations *p* through which the gas issues, and it is this upper surface that forms the real surface of the burner.

100 To the end of the mixture supply tube is fixed a conical or other appropriately shaped covering *o* which projects into the burner head and is formed with rows of small perforations *r* through which the mixture of gas 105 and air streams on passing into the burner

head. By virtue of this so-called gas distributer, an equal distribution of the mixture is obtained on the surface of the burner, so that the flame spreads over the whole 5 burner and has in every part of it the same degree of heat.

Burners that are provided with a gas distributer and a system for simultaneously regulating the mixture of air and gas, as 10 hereinbefore described, can not only present a much larger surface than known burners for gas at ordinary pressure, but the flame is at all parts of equal size and equally hot, by reason of the complete and intimate mixture 15 of the gas with the air; and moreover by virtue of equal distribution of the mixture on the surface of the burner, incrustation and the formation of soot are entirely prevented.

What I claim is:

A gas burner comprising a burner head, an air and gas mixing chamber, a gas inlet leading to said mixing chamber said gas inlet being disposed in a horizontal plane,

a conducting tube leading from said mixing 25 chamber to said burner head, an air inlet located above the mixing chamber and at right angles to the gas flow, and means for controlling simultaneously the supply of proportional quantities of gas and air to 30 said mixing chamber comprising a rotary gas cock controlling the said gas inlet; a rotary air valve controlling the said air inlet; the said gas cock and air valve being located one behind the other and each rotating around an axis perpendicular to the gas flow; and means connecting together said gas cock and said air valve, said connection being such that the gas cock and air supply valve simultaneously describe equal angles 35 about their axes.

In testimony whereof, I have signed my name to this specification in the presence of two subscribing witnesses.

PIERRE THEODORE ALBERT LASSCHUIT.
